UNITED STATES PATENT OFFICE.

JOHN A. FORSYTH, OF FREDERICKTOWN, PENNSYLVANIA, ASSIGNOR OF ONE-THIRD
TO ROBERT E. DRUM, OF CALIFORNIA, PENNSYLVANIA, AND ONE-THIRD TO HARRY
C. DRUM, OF COAL CENTER, PENNSYLVANIA.

COMPRESSED-AIR LOCOMOTIVE.

1,081,377.

Specification of Letters Patent. Patented Dec. 16, 1913.

Application filed June 23, 1913. Serial No. 775,315.

To all whom it may concern:

Be it known that I, JOHN A. FORSYTH, a citizen of the United States, residing at Fredericktown, in the county of Washington 5 and State of Pennsylvania, have invented new and useful Improvements in Compressed-Air Locomotives, of which the following is a specification.

My invention relates to locomotives operated by compressed air, but is applicable to other engines than locomotives, and to engines employing other motor fluid than compressed air.

The object of my invention is to simplify 15 the construction of compound engines by omitting various valves and operating devices and by making the operation or control practically automatic, except with respect to the throttling devices, which I leave 20 under the control of the engineer. Heretofore it has been the practice to control the passage between the auxiliary tank and the interheater by hand or foot or both. I control this passage automatically, as will be 25 explained presently.

Other objects are to improve the valves and other details.

Referring to the accompanying drawings, Figure 1 shows a compound compressed air engine diagrammatically, well known parts being omitted. Figs. 2 and 3 are sections of two valves which I prefer to use, the former controlling the passage to the auxiliary tank and the latter from the auxiliary tank to the 35 interheater. Fig. 4 is an elevation of the interheater valve shown in Fig. 2. Fig. 5 is a perspective view of a detail of the valve shown in Fig. 3.

On Fig. 1, 1 represents a pipe leading 40 from the main tank 1^a in which the compressed air may have a pressure of 800 pounds or more per square inch. This pipe is connected to the inlet 2 of the valve A (Fig. 2) whose outlet is connected to the 45 inlet of the reducing valve B. The outlet of the latter is connected by the pipe 3 to the auxiliary tank 4. This tank is connected by the pipe 5 to the inlet of the throttle valve C, whose outlet is connected by the 50 pipes 6 to the valve-chest 7 of the high-pressure cylinder 8. The cylinder 8 exhausts through the pipe 9 into the well-known interheater 10, the latter being connected by the pipe 11 to the valve-chest 12 of the low-

pressure cylinder 13. The exhaust from the 55 cylinder 13 passes through the pipe 14 into the interheater stack-flue or chamber 15 where it combines with the air drawn through the interheater and is discharged through the contracted portion 16 of the 60 flue. 17 represents the connecting rod driven by the cylinder 8, and 18 the connecting rod driven by the cylinder 13. These connecting rods lead in the usual manner to the crank-pin of the drive-wheel of the locomotive, the details of which form no part of the present invention, and are well-known. The auxiliary tank 4 is connected by the pipes 19 to the inlet 20 of the valve D (Fig. 3), its outlet being connected to the interheater 10 by the pipe 21. 22 is the throttle lever operated by the handle portion 23. The lever 22 is pivotally connected by the link or rod 24 to the vertical arm of the bell-crank lever 25, the horizontal arm thereof 65 being pivoted to the valve rod or stem 26 of the valve A. The vertical arm of the lever 25 is pivotally connected by the link 27 to the vertical arm of the bell-crank lever 28, whose remaining arm 29 operates the throttle valve 30 in the well-known manner.

The principal novelty of the present invention lies in the connections, including the valve D, between the auxiliary tank 4 and the interheater 10, in the valve A, and in the manner of connecting the valves A and C so that both may be controlled by the throttle lever 22. The link 27 is provided with a slot 31 in which the pivot 32 on the lever 25 works so that the lever 25 is operated in advance of the lever 28, permitting the auxiliary tank to be charged without permitting any compressed air to pass to the valve chamber 7 until the operator desires to allow it to do so.

Referring now to Figs. 2 and 4, the valve casing *a* is provided with the valve-seat *b* to which the valve *c* is adapted. The valve *c* has its upper end formed into a piston which reciprocates in the cylinder *d* in the upper extension *e* of the casing *a*. The cylinder *d* is closed at the top by the screw-plug *f*. The valve *c* has the hollow *g* which communicates with the inlet by the passage *h* and with the outlet by the enlarged opening *i* around the stem *g*. The upper portion of the opening *i* is formed into a seat *j* for the auxiliary valve *k* loosely mounted on

the reduced extension *l* of the stem 26 in the hollow *g*. The top of the valve *c* is provided above the hollow *g* with the screw plug *m* of a size to permit the valve *g* to be removed from the valve *c* when the plug is removed. The bottom of this plug forms a seat for the upper end of the valve *k*. The valve *k* is provided with the vertical passage *n* around the extension *l*, the upper end of the valve *k* around the passage *n* being formed into a seat for the valve *o* on the top of the said extension *l*. The plug *m* has the central opening *p* through which air in the cylinder *c* can pass to the passage *n*. The passage *n* is connected to the interior of the valve casing below the valve *k* by the passage *q* in the stem 26 when the stem 26 is raised as shown. The extension *l* has some vertical lost motion in the valve *k*, so that the stem 26 will move up slightly before engaging the bottom of the valve *k* which rests on a shoulder around the extension *l*. When it is desired that no air shall pass through the valve *A*, the lever 22 is pushed to the left until the valve *k* rests on its lower seat *j*, the valve *c* rests on its seat *b*, and the valve *o*, rests on its seat. The pressure of the air in the inlet 2 has access to the top of the valves *c*, *k*, and *o*, each of which has a larger area subjected to downward pressure than to upward pressure, since a large part of each valve is exposed to a lower pressure in the exhaust side of the casing *a*. When it is desired to open the valve *o*, which is held on its seat by a very great pressure, assuming the pressure in the inlet 2 to be 850 pounds per square inch, the lever 22 is moved to the right first a short distance, just sufficient to cause the stem 26 to leave its seat and the valve *k* to be lifted from its seat *j* to its seat against the plug *m*. The compressed air in the cylinder *d* escapes into the valve chamber by way of the opening *p*, the valve *o*, and the passages *n* and *g*, and the air from the inlet 2 passes into the chamber below the valve *c* by way of the passage *h*, the hollow *g*, and opening *i*, whereby the compressed air above the valve *c* may escape and the compressed air in the inlet 2 has access to the bottom of the valves *c* and *k*. After a short time the pressure beneath the valve *k* is raised so that the operator can easily move the throttle lever farther to the right and cause the stem, acting mechanically through the auxiliary valve *k*, to lift the valve *c* from its seat, the air in the cylinder *c* escaping past the valve *o*. It is readily seen that the labor required to lift the valve *c* from its seat is materially reduced by my improvements.

Referring now to Figs. 3 and 5, the valve *D* has the casing 33, having the inlet passage 34 and the outlet passage 35, preferably at diametrically opposite places. The casing 33 has a bore 36 extending from the

bottom upwardly. Within this bore are the pistons 37 and 38 connected together by the reduced stem 39, the latter lying preferably in line with the inlet 34 and the outlet 35, and the pistons lying on opposite sides of the said inlet and outlet. These pistons are provided with cup packings which prevent the passage of air between the pistons and the contiguous portions of the casing 33. The lower end of the bore 36 is closed by the screw-plug 40 on which the piston 41 rests. This piston is provided with suitable packing rings fitting against the wall of the bore 36. The casing 33 has a top extension 42 which contains the expansion spring 43 having its lower end resting on the piston 37 and its upper end beneath the disk 44 adjustable lengthwise of the extension 42 by means of the screw 45 working in the end of the said extension. The spring pushes the pistons 37 and 38 down on the piston 41 when permitted to do so, and regulates the pressure required to lift the said pistons, as will be explained presently. The casing 33 is provided with the valve 46 which controls the passage of air from the inlet 34 to the space between the piston 41 and the plug 40. The valve 46 is urged toward its seat in the top of the chamber 47 by the spring 48 compressed between the lower end of the valve and the plug 49. 50 is a passage leading from the chamber 47 to the space between the piston 41 and the plug 40. The valve 46 contains an auxiliary valve 51 which seats by downward pressure on the top of the valve 46. The interior of the valve 46 has the hollow 52' and has the passages 52 connecting the said hollow to the annular chamber 47 surrounding the valve 46. The hollow 52' communicates with the passage 34 when the valve 51 is lifted. The passage 53 in the casing 33 connects the outlet passage 35 with the space between the pistons 38 and 41. 54 represents an arc-shaped valve fitting the wall of the bore 36 about the outlet passage 35. It has the opening 55 which connects the passage 35 with the space between the pistons 37 and 38 and consequently with the inlet passage 34 when the pistons are at their lowest limits. The valve 54 has a pair of arms or projections 56 extending into the stems 39 and urged outwardly by the expansion springs 57.

The pressure in the pipe 1 may be 850 pounds per square inch. The regulator B may be set so that the pressure in the auxiliary tank 4 is limited to 250 pounds per square inch. The auxiliary valve 46 may be adjusted to open when the pressure in the inlet is 75 pounds per square inch and cause the pistons 37, 38, and 41 to be raised and the valve 54 to close the outlet passage 35.

To start the locomotive, the throttle lever is moved to the right sufficiently to open the valve A in the manner already described. The highly compressed air passes from the valve A through the reducer to the auxiliary tank 4. The rising pressure in the tank 4 passes through the valve D, and the interheater 10 to the cylinder 13, and will operate the rod 18 if it is not on the dead center. If this rod is on the dead center, the pressure in the cylinder 13 is not effective, of course. The pressure soon builds up in the tank to 75 pounds whereupon the pressure forces the valve 46 down and compressed air passes through the chamber 47 and the passage 50 and forces the pistons 37, 38, and 41, causing the valve 54 to close the passage 35 which is open to the interheater 10 by way of the pipes 21, and to the exhaust of the high-pressure cylinder 8 by way of the pipe 9, the interheater 10, and the pipes 21. If the locomotive does not start after the engineer has opened the valve A and before he opens the valve C, by reason of the rod 18 being on the dead center, he pulls the lever 22 farther to the right, so that the pin 32, which traveled in the slot 31 during the first movement of the lever 22, will now pull the lever 28 and open the throttle valve C, whereupon the air in the tank 4 will pass to the cylinder 8 and cause the rod 17 to operate. If for any reason the pressure in the valve D has failed to close the valve 54, the pressure from the exhaust of the high cylinder will pass from the interheater through the pipes 21 and the passage 53 in the valve D and cause the pistons 37 and 38 to be lifted, thereby moving the valve 54 over the passage 35, and preventing the air in the tank 4 from passing through the valve D. It is necessary that the valve 54 be closed when the cylinder 8 is active as the valve D when open would form a by-pass for the cylinder 8. When the pressure in the valve D is reduced, the pistons therein are caused to descend by the action of the spring, the air beneath the piston 41 obtaining relief through the passage 50 and past the valve 51 in the valve 46.

I do not desire to be limited to the details and combinations shown as many changes may be made therein without departing from the spirit of my invention.

55 I claim—

1. In a compressed air compound engine, a tank to contain compressed air, a high-pressure cylinder, a low-pressure cylinder, an interheater connected to the exhaust of the high-pressure cylinder, to the valve-chest of the low-pressure cylinder, and to the air tank, and an automatic valve in the connection to the air-tank for closing the said connection when the pressure in the tank exceeds a predetermined pressure.

2. In a compressed air compound engine, a tank to contain compressed air, a high-pressure cylinder, a low-pressure cylinder, an interheater connected to the exhaust of the high-pressure cylinder, to the valve-chest of the low-pressure cylinder, and to the air-tank, and an automatic valve in the connection to the air-tank for closing the said connection when the pressure in the tank exceeds a predetermined pressure, and when the high-pressure cylinder is exhausting into the interheater. 70 75

3. In a compressed air compound engine, a tank to contain compressed air, a high-pressure cylinder, a low-pressure cylinder, an interheater connected to the exhaust of the high-pressure cylinder, to the valve-chest of the low-pressure cylinder, and to the air-tank, and a valve in the connection to the air-tank, the said valve comprising a casing, having a passage therethrough to establish communication between the air-tank and the interheater, a valve in the casing for closing the said passage, and bypassages for admitting pressure from the air-tank for closing the valve when the pressure in the air-tank exceeds a predetermined value. 80 85 90

4. In a compressed air compound engine, a tank to contain compressed air, a high-pressure cylinder, a low-pressure cylinder, an interheater connected to the exhaust of the high-pressure cylinder, to the valve-chest of the low-pressure cylinder, and to the air-tank, and a valve in the connection to the air-tank, the said valve comprising a casing, having a passage therethrough to establish communication between the air-tank and the interheater, a valve in the casing for closing the said passage, and bypassages for admitting pressure from the air-tank and from the interheater for closing the valve when the pressure in the air-tank exceeds a predetermined value and when the high-pressure cylinder is exhausting into the interheater. 95 100 105 110

5. In a compressed air compound engine, a tank to contain compressed air, a high-pressure cylinder, a low-pressure cylinder, an interheater connected to the exhaust of the high-pressure cylinder, to the valve-chest of the low-pressure cylinder, and to the air-tank, and a valve in the connection to the air-tank, the said valve comprising a casing, having a passage therethrough to establish communication between the air-tank and the interheater, an unbalanced valve in the casing for closing the said passage, and a passage for connecting the interheater with the larger area of the valve, 115 120 125 whereby the exhaust from the high-pressure cylinder may close the valve.

6. In a compressed air compound engine, a tank to contain compressed air, a high-pressure cylinder, a low-pressure cylinder, 130

- an interheater connected to the exhaust of the high-pressure cylinder, to the valve-chest of the low-pressure cylinder, and to the air-tank, and a valve in the connection 5 to the air-tank, the said valve comprising a casing, having a passage therethrough to establish communication between the air-tank and the interheater, an unbalanced valve in the casing for closing the said 10 passage, a passage connecting the air-tank with the larger area of the valve, and an auxiliary valve in the last passage, unseated by pressure above a predetermined value in the air-tank.
- 15 7. In a compressed air compound engine, a tank to contain compressed air, a high-pressure cylinder, a low-pressure cylinder, an interheater connected to the exhaust of the high-pressure cylinder, to the valve-chest of the low-pressure cylinder, and to the air-tank, and a valve in the connection to the air-tank, the said valve comprising a casing, having a passage therethrough to establish communication between the air- 20 tank and the interheater, an unbalanced valve in the casing for closing the said passage, a passage connecting the air-tank with the larger area of the valve, an auxiliary valve in the last passage, unseated by pressure above a predetermined value in the air-tank, and a valve carried by the auxiliary valve and opening to exhaust the pressure in the larger area of the valve in the said 25 connection between the air-tank and interheater.
- 30 8. In a compressed air compound engine, a main high-pressure tank, an auxiliary tank, a high-pressure cylinder connected to the auxiliary tank, a throttle in the connection 35 between the auxiliary tank and the cylinder, a low-pressure cylinder, an interheater connected to the low-pressure cylinder, to the exhaust of the high-pressure cylinder, and to the auxiliary tank, a check-valve in the 40 connection between the interheater and the auxiliary tank for closing the connection when the pressure in the auxiliary tank reaches a predetermined pressure suitable 45 for the low-pressure cylinder, a second throttle for admitting air from the main tank into the auxiliary tank, and means for actu- 50 ating the second throttle in advance of the first throttle.
9. In a compressed air engine, a main tank for containing highly compressed air 55 an auxiliary tank connected to the main tank, a throttle in the connection between the tanks, the said throttle comprising a casing containing an unbalanced hollow valve seated by the pressure from the main tank, 60 the hollow communicating with the connection to the main tank, a piston on the said valve opposite its seating face, a closed chamber for the piston, an auxiliary valve reciprocatory in the said hollow and having 65 a seat at the top of the hollow to close a passage in the main valve to the chamber, and a seat at the bottom of the hollow to close a passage in the main valve to the exhaust side of the main valve seat, and a 70 valve stem having lost motion in the auxiliary valve and having an auxiliary valve thereon to close an exhaust passage in the first auxiliary valve leading to the said chamber.
- 75 10. In a compressed air compound engine, a tank to contain compressed air, a high-pressure cylinder, a low-pressure cylinder, means for connecting the exhaust of the high-pressure, the valve-chest of the low-pressure cylinder, and the air-tank, and an automatic valve in the connection to the air-tank for closing the said connection when the pressure in the tank exceeds a predetermined value.
- 80 11. In a compressed air compound engine, a tank to contain compressed air, a high-pressure cylinder, a low pressure cylinder, means for connecting the exhaust of the high-pressure, the valve-chest of the low-pressure cylinder, and the air-tank, and an automatic valve in the connection to the air-tank for closing the said connection when the pressure in the tank exceeds a predetermined pressure, and when the high-pressure 85 cylinder is exhausting into the interheater.
